ROBERT COOKE CHATTIN, OF MOUNTAIN HOME, IDAHO, ASSIGNOR TO CHATTIN TOOL COMPANY, OF BOISE, IDAHO, A CORPORATION OF IDAHO.

IRRIGATION DITCHER.

Application filed October 30, 1923. Serial No. 671,760.

This invention relates to an irrigation ditcher, and the objects of the invention are as follows:

First, to provide a device for the construction of flat bottomed feed or lateral ditches for irrigation purposes by depositing the dirt removed upon the lower bank of the main or head ditch and leaving the constructed ditch in the proper condition for irrigating corrugated land; second, to provide a device to be used for the construction of flat bottomed ditches by depositing the dirt removed successively upon each side of the ditch; third, to provide a device of the character above described, which is adjustable for the construction of ditches of varying widths and depths and varying contour of banks; fourth, to provide a device of the character above described, having a cutting edge or share which may be easily replaced or which may be readily detached for the purpose of resharpening; fifth, to provide a device of the character above described, which will satisfactorily remove from the bottoms and banks of ditches all vegetation which may be in the path of the device when in operation and which would otherwise seriously interfere with irrigation, depositing same upon the banks with other dirt and débris removed from the ditch; and sixth, to provide a device of the character above described, which is simple, strong and durable in construction and which will not easily get out of order, and which may be readily manufactured at a comparatively slight expense from material and by means of facilities ordinarily available.

Other objects and advantages of the invention reside in certain novel feature of construction, combination and arrangement of parts which will be hereinafter more fully described and particularly pointed out in the appended claims, reference being had to the accompanying drawings forming part of this specification, and in which:

Figure 1 is a perspective view, illustrating the preferred embodiment of the invention;

Figure 2 is a plan view thereof;

Figure 3 is a view in side elevation;

Figure 4 is a fragmentary view in vertical section, taken on line 4—4 of Figure 2 and looking in the direction of the arrows; and

Figure 5 is a similar view in horizontal section, taken on line 5—5 of Figure 1 and looking in the direction of the arrows.

Referring to the drawings, wherein for the sake of illustration is shown the preferred embodiment of the invention, the numeral 10 designates generally the landside of the ditcher which consists of a forward plate 11 and an elongated rearward plate 12. The plates 11 and 12 are constructed of metal and are arranged vertically. In assembling the plates 11 and 12 their lower edges are arranged at an angle to each other which is slightly less than 180° and which is preferably varied between 175° and 180°, this angle being indicated at *a* in Figure 1. By this arrangement of the plates the forward end or nose of the plate 11 is given a slightly down lead in operation and the rearward plate 12 rides upon the extreme rear end of the plate. Bolts and nuts 13 are employed for securing the plates 11 and 12 to each other, the plates slightly overlapping, as shown in Figure 3 and of course having alined bolt holes for the reception of the bolts 13. Preferably the plate 11 is provided with countersinks for receiving the heads of the bolts 13. It is also to be noted that the plates 11 and 12 are vertically disposed or arranged.

A steel share 15 is detachably secured to the front end of the plate 11 by a bolt and nut 16. Above the steel share 15 a mold board 17 is arranged and is secured at its forward edge to the plate 11 by bolts and nuts 18. The front end of the steel share 15 and a portion of the front end of the mold board 17 which lies below the extension 14 of the plate 11, which will later be described, as well as the portion of the plate 11 which is contiguous with the front end of the steel share 15 and the portion of the front end of the mold board which lies below the extension 14 are sharpened or beveled to present a sharp cutting edge. The mold board 17 and share 15 are connected to each other by a connecting strip 19 which is secured both to the mold board and to the share by bolts and nuts 20. This connecting strip is arranged on the inner side of the mold board and share. Common means is provided for connecting the mold board and the share to the plate 12 of the landside and preferably this means includes a short connecting strip 21 arranged on the inner side of the share 15 and mold board 17 and secured to these parts by bolts and nuts 22, the connecting strip 21 having a lug 23 pivotally connected to one end of a link 24. The other end of the link 24

24 is adapted to be selectively pivoted, as at 25, to any one of a number of pivot holes 26 provided in an angle piece 27 bolted to the plate 12 of the landside. This common means 5 for adjustably connecting the mold board and share to the plate 12 of the landside is shown to advantage in Figures 2, 4 and 5. In this manner the mold board and share are adjustably though positively connected to 10 the plate 12 of the landside. It will be understood that by varying the connection of the link 24 to the angle piece 27 the angular relation of the mold board and share to the landside may be varied so that the ditcher 15 can be adjusted to produce ditches of varying widths. In making an adjustment of the link 24 it will of course be understood that the bolts 16 and 18 are first loosened and after which tightened. The bolt holes in the 20 share 15 and mold board 17 which accommodate the bolts 16 and 18 respectively are sufficiently larger than the bolts 16 and 18 to admit of the adjustment described. The point of the share 15 extends slightly below 25 the forward portion of the landside, as indicated at 15° and the lower side of the share is curved slightly forward and outward and is sharpened for about two-thirds of the distance from the front to the rear end of the 30 share as indicated at 15°.

A wing 30 is provided and extends upwardly from the rear end of the share 15 and mold board 17, as shown in Figures 1 and 3, the wing also diverging from the landside 35 10, as shown in Figure 2. This wing 30 is transversely curved and the degree of its transverse curvature progressively increases toward its lower end. The transverse curvature of the wing gives it a trough-like character 40 to enable it to better carry or conduct the earth or the like up and out of the ditch. The forward end of the wing 30 is adjustably connected to the mold board 17 and share 15. As shown to advantage in Figure 45 4 this means includes a pivot bolt 31 which extends through pivot openings provided therefor in the wing 30 and in the share 15. Of course the bolt 31 has a nut threaded 50 thereon which may be tightened when the parts have been adjusted. Two bolts 32 are provided and extend through arcuate slots provided therefor in the wing 30. One of the bolts 32 extends through a pivot hole provided in the share 15 and the other bolt 32 55 extends through a bolt hole provided therefor in the mold board 17. The bolts 32 also have nuts threaded thereon which may be tightened when the parts are adjusted. Adjacent the upper part of the forward end of 60 the wing 30 it is provided with an arcuate series of bolt holes 33 adapted to be selectively aligned with a single bolt hole provided in the mold board 17. A bolt 34 is extended through the aligned hole of the series 33 and 65 the single bolt hole of the mold board 17 and

has a nut threaded thereon and tightened to hold these parts in adjusted position. The heads of the bolts 31, 32 and 34 are received in countersinks provided in the share 15 or the mold board 17 as the case may be. By 70 loosening the nuts on the bolts 31 and 32 and by removing the bolt 34 the wing 30 may be adjusted about the bolt 31 to raise and lower the wing. After the desired adjustment has been made the bolt 34 is reinserted through the aligned bolt holes in the mold board and wing 20 and its nut is put in place and tightened and the nuts on the bolts 31 and 32 are tightened to hold the parts in adjusted 75 position. 80

Means is provided for adjustably though positively connecting the wing 30 to the plate 12 of the landside. This means preferably includes a rigid connecting rod 35 having one end pivotally connected to the wing, as at 36. 85 This pivot connection 36 is preferably obtained by forming an eye 37 at one end of the connecting rod and engaging this eye with a curved portion 38 of a bracket 39 riveted or otherwise secured to the wing. This permits the rod 35 to pivot either horizontally or vertically with respect to the mold board 30. The opposite end of the rod 35 from that connected to the wing 30 is formed with a yoke pivoted to the main portion of the rod 35 or made sufficiently large or bendable to admit of the described adjustment and this yoke 40 embraces the horizontal flange 41 of the angle piece, designated generally at 42 and bolted to the inner side of the plate 12 of the landside. The horizontal flange 41 of the angle piece is provided with a series of bolt holes 43. The arms of the yoke 40 are provided with aligned aperture 44 adapted to be brought into registration with any one of the openings 43 and pivotally connected in such position by the pivot bolt 45. By varying the connection of the rod 35 to the angle piece 41 the wing 30 may be adjusted horizontally in accordance with the horizontal or angular adjustment of the share 15 and mold board 17. At the same time the rod 35 is so pivotally connected to the wing 30 as to permit the same to be adjusted vertically. The adjustment of the wing 30 must also be 90 accompanied by adjustment of the arm 35 along the angle piece 42. 95

A platform, designated generally at 50, is provided and includes an elongated angle iron 51 having its vertical flange bolted, riveted or otherwise suitably secured to the plate 12 of the landside. The horizontal flange of the angle iron 51 extends toward the mold board 17 and wing 30 and this horizontal flange carries a flat metallic plate or piece 52, strips 53 being secured to the horizontal flange of the angle iron and to the plate 52 for the purpose of mounting the plate on the angle iron. 100

A socket 55 is bolted or otherwise suitably 105

secured to the wing 30, and is adapted to receive one end of a handle 56. The handle 56 is curved so as to extend upwardly and laterally from the wing 30 and so as to overlie the platform 50.

At the forward end of the ditcher, a hitch is provided for adjusting the draw bar pull or draft vertically and horizontally to allow for variations desired in depth of ditches and 10 to correct or eliminate the side draft. This hitch includes a bar 60 having a lug 61 at one end adjustably secured to an extension 14 of the plate 11 by means of a bolt and nut 62 selectively cooperable with any one of a series 15 of bolt holes 63 provided in the extension 14 and also cooperable with a bolt hole provided in the lug 61 and aligned with one of the bolt holes 63. The bar 60 is itself provided with a series of openings 64 and has its outer end 20 connected, as at 65, to one end of a twisted arm 66, the other end of the arm being secured by a bolt and nut 67 to the mold board 17.

The ditcher is adapted for use in a construction of flat bottom feed or lateral ditches 25 for irrigation purposes. When it is in use it is drawn along by a horse, tractor or the like, and the draft is transmitted to the ditcher by a draw bar attached to any one of the openings 64. By thus transmitting the draft 30 to the ditcher all side draft is eliminated or corrected. By varying the adjustment of the lug 61 of the bar 60 to the extension 14 the draft can also be utilized to regulate the depth of cut. The width of the ditch to be 35 dug is determined by the angular relation of the share 15 and mold board 17 to the landside 10. This angular relation is varied by adjusting the connection of the lug 24 on the angle piece 27 in the manner above described. 40 The earth cut or excavated by the share travels up the mold board 17 onto the wing 30. The trough-like wing carries the earth thus excavated laterally and upwardly and deposits the same on the side of the ditch. This 45 wing 30 is adjustable to allow for adjustment of the share and mold board and also in order that it can effectively carry out its functions in digging ditches of various depths. The operator stands on the platform 50 and by 50 changing his riding position, either forward or backward, can conveniently vary the plowing effect of the ditcher. The ditcher may be tilted at will by the operator by means of the handle 56, the operator grasping the handle 56 and swinging his weight to one side or the other of the ditcher as may be necessary. This handle 56 also facilitates manipulation of the ditcher and the transportation 55 of the same from place to place.

60 It is to be noted that the angle iron 51 serves not only as a support for the platform 50 but serves also to take the bending stresses of the plates 11 and 12.

65 Preferably the lower edge of the wing 30 adjacent the share 15 is sharpened to con-

stitute a cutting edge and is tipped slightly outward.

I claim:

1. In a ditching machine, a landside, the earth contacting surface of which occupies a substantially vertical plane and having a forward portion provided with a rearwardly sloping edge and a rear portion, the bottom edge of which extends downwardly at an angle to the bottom edge of the said forward portion, a share and mold board connected together and commonly attached at the forward end to the said sloping edge of the forward portion of the land side in a manner to permit angular adjustment in a horizontal plane, the said share portion having a point extending below the lower edge of the forward portion of the landside, means for adjusting the angular relation of the share and mold board relative to the landside, a wing member connected with the rear end of the share and mold board and movable therewith in the adjustment of the angular relation of the share and mold board relative to the landside, and means for angularly adjusting the wing member in a vertical plane relative to the share and mold board.

2. In a ditching machine, a land side consisting of a long comparatively narrow plate occupying a substantially vertical plane and a plate forming a continuation thereof in the same plane at the forward end, the said forward end having a rearwardly sloping ground entering forward edge for a portion of its width and an upper forwardly projecting portion, a draft appliance connected with the said forwardly projecting portion, the said first named long plate having a downwardly sloping bottom edge extending to a point below the bottom edge of the said forward continuation portion, a mold board and share connected together and commonly attached to the rearward sloping edge of the forward land side plate, in a manner to permit adjustment in a horizontal plane of the angular relation of the share and mold board with the plate, said share having a point at its forward edge extending below the plane of the bottom edge of the land side portion to which it is attached and the share and mold board having a common forward edge sloping rearwardly to correspond with the rearwardly sloping edge of the forward portion of the land side and providing therewith an earth cutting edge, and a wing member detachably connected with the rear end of the share and mold board, means for angularly adjusting the wing member in a vertical plane relative to the share and mold board, and a draft appliance connected with the said forwardly projecting end portion of the land side and arranged to be relatively adjusted in a vertical plane.

ROBERT COOKE CHATTIN.
